SIPHONIC FLUSHING APPARATUS

Jesse C. Owens, Los Angeles, Calif.

Application February 24, 1947, Serial No. 730,447

3 Claims. (Cl. 4—44)

1

This invention relates to flushing apparatus of the type commonly used in water closet systems, and more particularly to flushing devices wherein the flow of water from a tank is controlled by a siphon rather than by a relatively undependable, short-lived and noisy check valve.

It is an object of my present invention to provide a flushing apparatus of the siphon type wherein the siphon element is movable and wherein the flushing action is started simply by lowering the siphon tube until it is submerged within water stored within the tank, with the result that water starts flowing by gravity over the high point of the siphon in sufficient volume to start siphonic action and without the necessity of opening any flushing valve, thus eliminating the noises which necessarily accompany actuation of the mechanical movements required for actuation of a flushing valve, as well as the hissing and gurgling noises coincident with the rushing of water through the relatively restricted space between a flushing valve and its seat.

It is another object to provide a siphon-actuated flushing apparatus of the character indicated wherein the flow of water from the storage tank is stopped automatically when water has been withdrawn from the tank in sufficient quantity for the upper surface of the water to fall below the intake end of the siphon, thus permitting air to be drawn into the siphon and consequently breaking the siphonic action, and wherein in the siphon tube itself rises to a position sufficiently elevated to dispose a substantial portion thereof above the high water level within the tank so that the siphon tube itself serves as the element preventing subsequent flushing action and leakage from the tank until the apparatus again is actuated to submerge the siphon tube.

Another object is to provide, in a specialized embodiment of the present invention, means for supplying an auxiliary flow of water to the siphon tube directly from the water supply, this auxiliary flow being maintained during the entire time when siphonic action takes place, thus causing a quantity of water considerably in excess of that stored within the tank to be delivered each time the flushing operation occurs.

A further object in this same connection is to provide means for restricting the flow of water by siphonic action, thus further prolonging the time during which the auxiliary flow from the water supply is maintained and further increasing the amount of water delivered each time the flushing apparatus is actuated.

The invention possesses other objects and fea-

tures of advantage, some of which, with the foregoing, will be set forth in the following description of the preferred forms of my invention which are illustrated in the drawings accompanying and forming part of the specification. It is to be understood that I do not limit myself to the showing made by the said drawings and description, as I may adopt variations of the preferred forms within the scope of my invention as set forth in the claims.

Referring to the drawings:

Figure 1 is a view taken in transverse vertical section through a flushing tank to show flushing apparatus embodying the present invention operably installed therein.

Figure 2 is an enlarged view taken in transverse vertical section through the flushing apparatus of Figure 1.

Figure 3 is an enlarged detail view partially in vertical section, showing a modified form of adaptor for mounting the flushing apparatus of the present invention within a flushing tank.

Figure 4 is a detail view in perspective of the flexible portion of the siphon tube of Figures 1 and 2.

Figure 5 is a view similar to Figure 1, showing a modified form of flushing apparatus of the present invention.

Figure 6 is an enlarged detail view in vertical medial section of the intake end of the siphon tube of Figure 5.

Figure 7 is a vertical, medial sectional view taken through a further modified form of siphon tube embodying principles of present invention.

Figure 8 is a horizontal, transverse sectional view taken upon the line 8—8 of Figure 7 with the direction of view as indicated.

Figure 9 is an exploded view of the packing elements employed for providing a fluid-tight, sliding joint between the telescopic sections comprising the siphon tube of Figure 7.

Figure 10 is a perspective view of the adjustable stop for the upper end of the spring employed as a portion of the telescopic siphon tube of Figure 7.

Figures 1 and 2 are illustrative of one embodiment of the flushing apparatus of the present invention operably installed in a flushing tank 11 of conventional design. The outlet pipe 12, whereby water discharged from the tank 11 is conducted to a toilet fixture (not shown), is illustrated as being in the form of an L rigidly secured to the bottom 13 of the tank by having its vertical upper end 14 fitted into the bore of a sleeve 16 extending downwards through a suit-

able opening 17 in the tank's bottom 13. A packing ring 18 is compressed tightly against the vertical portion of the L 12 by a gland nut 19 threaded upon the lower end of the sleeve 16. The sleeve 16 is also threaded through a nut 21 bearing against the under surface of the tank's bottom 13 so as to draw a head 22 formed on the upper end of the sleeve 16 tightly downwards against a suitable packing 23, preferably of conical form so that its lower end can be squeezed into the opening 17 in the tank's bottom 13.

This type of connection for the outlet pipe 12 is conventionally employed in flushing tanks in which control is exercised over the discharge of water by a ball check valve which must be lifted off its seat to permit escape of water from the tank into the outlet pipe; and that modification of my improved flushing apparatus illustrated in Figures 1 and 2 is intended as a replacement for the conventional ball check valve by the simple expedient of removing the ball valve and inserting as a replacement therefor the lower end 31 of the outlet portion 32 of the movable siphon tube 33 which constitutes an important part of my improved flushing apparatus. The upper surface of the head 22 is provided with a concavity 34 designed to function as the valve seat for the conventional ball check valve; and after the conventional valve has been removed this concavity 34 provides a convenient recess for a conical sealing gasket 35 of resilient material pressed downwards into the concavity 34 by an annular plate 36 rigidly and preferably permanently secured to the tubular lower end 31 of the outlet portion 32 of the siphon tube.

A frusto-conical portion 37 of the siphon's outlet portion 32 is provided adjacent the discharge end thereof, and is adapted to compress a complementarily formed sealing gasket 38 by squeezing it tightly against the bore of the sleeve 16 when the frusto-conical portion 37 is thrust downwards into the sleeve, thus enhancing the efficiency of the fluid-tight seal established between the outlet portion 32 of the siphon tube 33 and the sleeve 16 when the siphon tube is mounted in operative position as illustrated in Figure 2.

Figure 3 shows a slightly modified arrangement for mounting the siphon tube in operative position. In this modification the lower end 41 of the outlet portion of the siphon tube is exteriorly threaded and is of sufficient length to extend through the bottom 42 of the tank to receive both a nut 43 and a packing gland 44 thereupon below the tank's bottom 42. By tightening the nut 43 the siphon tube is made rigid with the tank's bottom 42 and a gasket 46 is compressed between a plate 47 carried by the siphon tube and the upper surface of the tank's bottom 42; and by tightening the gland 44 another packing ring 48 is tightened both against the extreme lower end of the siphon's outlet portion and against the outer periphery of the discharge pipe 49 which leads from the flush box to the toilet fixture.

Referring again to Figures 1 and 2, preferably an obliquely extending portion 51 is provided as a part of the lower end of the siphon's outlet portion 32; and to the upper end of this obliquely extending portion 51 a flexible tube 52 is secured as by a strap clamp 53. Preferably the tube 52 is composed of rubber or composition of a consistency which makes the tube reasonably flexible and still possessed of a sufficient degree of resiliency to retain its shape, considered both with respect to its being of tubular form and also its

containing a bend 54 of substantially 90°. This bend may be provided by molding the flexible tube 52 with preferably a plurality of corrugations 56 along the inner side of the bend so as to facilitate flexing the siphon tube from its normal position as indicated in full lines in Figure 2 to that position which is illustrated in broken lines in that figure.

The inherent resiliency of the material of which the flexible tube is composed preferably is sufficient for the retention of the siphon tube in its uppermost of normal position; however, as a precautionary measure, a reinforcing spring 57 may be employed, this spring preferably being in the form of a flat, elongated strap of non-corrosive material, rigidly secured at its lower end to the stationary portion of the siphon's outlet end as by being engaged under the same clamp 53 as that which is relied upon to retain the flexible tube 52 thereupon. The spring 57 is flexed so as substantially to follow the curvature of the outside portion of the bend 54 and the upper end of the spring 57 is slidably engaged within an eye 58 which conveniently is provided upon the clamp 59 which is employed to fasten the upper end of the flexible tube 52 to the portion of the siphon tube which communicates therewith.

This portion of the siphon tube 33 comprises an inlet portion 61 and a bend 62. The inlet portion 61 opens at its lower end 63 to the interior of the tank 11, and from the lower end 63, the inlet portion 61 inclines upwards to one end of the bend 62, the other end of the bend 62 being in communication with the upper end of the flexible tube 52 which inclines downwards from the bend 62 around the bend 54 and into communication with the discharge pipe 12.

The parts are so proportioned and arranged that when the siphon tube occupies its normal position the bend 62 is disposed above the high water level 66 within the tank 11. However, when the flexible tube 52 is flexed in such a manner as to increase the curvature of the bend 54, the upper portion of the siphon tube will be lowered far enough to submerge all of the siphon tube within the tank 11, provided the tank is filled to its normal capacity.

When the outlet portion 31 of the siphon tube 32 is empty and the bend 62 is disposed above the water line 66, of course water will not flow through the siphon tube 31 because it cannot rise within the inlet portion 61 far enough to flow over the bend. However, when the bend 62 is submerged, water will start to flow through the siphon tube, entering the inlet end 63 and flowing through the inlet portion 61 around the bend 62 and through the outlet portion 31 and into the outlet pipe 12. Thereafter, the water flowing by gravity downwards through the outlet portion will develop siphonic action within the siphon tube in accordance with well-known principles and cause water to continue to flow through the siphon tube, even though the siphon tube may return to its initial position with a portion thereof elevated above the level of the water, until a sufficient quantity of water has been withdrawn from the tank 11 to lower its level to that of the opening 63 in the inlet end of the siphon tube. When this occurs, air will be drawn into the siphon tube, breaking the siphonic action and cause discontinuance of flow from the tank 11 to the discharge pipe 12.

Thus it may be seen that flow of water to perform the flushing operation is both started and

stopped without necessitating the use of any check valve and consequently with the elimination of noises which necessarily accompany the manipulation of the mechanical connections necessary for the operation of any such valve. Moreover, water flows through the siphon tube smoothly and without the degree of restriction which occurs when water is required to flow between an opened ball check valve and its seat, with the result that the hissing and gurgling noises usually accompanying the flushing of a conventional toilet fixture are largely eliminated by the apparatus of the present invention.

A transversely extending shaft 71 is mounted for rocking movement on the front wall of the tank 11 and the shaft 71 extends through the front wall so that a manually operable handle 72 rigid with the shaft 71 can be positioned in a conveniently accessible location on the front of the tank. Within the tank 11 the shaft 71 also carries a finger 73 rigid therewith and extending laterally therefrom in that direction which causes it, when the handle 72 is in normal position, to seat within a recess 74 of an arm 76 which is pivotally mounted within, and which extends laterally from a valve housing 77 supported upon the upper end of a water inlet pipe 78.

The arm 76 is provided with a second recess 79 so arranged that when the arm 76 is at its upper extreme of movement the recess 79 is spaced from the shaft 71 a shorter distance than the spacing between the shaft 71 and the recess 74. Consequently when the handle 72 is depressed from its normal position, turning the shaft 71 in a counter-clockwise direction as viewed upon Figure 1, the finger 73 will be removed from the recess 74 and, after forcing the arm 76 downwards substantially to the position illustrated in Figure 1, seat within the second recess 79.

To the outer end of the arm 76 is secured a rod 81 carrying upon its outer end a float 82. The float 82 and rod 81 normally retain the arm 76 in its upper position because of the tendency of the float 82 to rest upon the upper surface of the water within the tank. The arm 76 extends into the valve housing 77 where it operates a suitable valve mechanism, the details of which need not be described in detail because they do not constitute an essential part of the present invention. For the purpose of this disclosure, it is necessary only to explain that when the arm 76 is in its uppermost position, the valve mechanism within the housing 77 is closed, but when the arm 76 is lowered therefrom to the position illustrated in Figure 1 or to a position lower than that illustrated, the valve mechanism will be opened, permitting water to flow from the supply pipe 78 through the valve housing 77 and to a delivery tube 83.

The delivery tube 83 leads through a valve housing 86; and beyond the valve housing 86 the delivery tube 83 is provided with an upwardly directed portion 87 to which a flexible tube 88 is secured, the latter serving as a nozzle and extending upwards into the lower end of the inlet portion 61 of the siphon tube. Just below the lower end of the flexible tube 88, the upwardly directed portion 87 of the supply tube is provided with a plurality of apertures 91 and with an upwardly opening cup 92, the bottom of which is below the apertures 91 and the flaring side wall 92 of which extends upwards beyond the level of the apertures 91.

Means are provided for imparting the neces-

sary movement to the siphon tube to submerge its upper portion and thereby institute the flushing operation. The shaft 71 carries a second arm 96 extending radially therefrom in substantially the opposite direction from that in which the handle 72 extends, with the result that when the handle 72 is depressed, the arm 96 will be raised. Consequently a weight 97 on the outer end of the arm 96 resists turning the shaft 71 in that direction in which it is caused to turn by depressing the handle 72; and it also urges the shaft 71 to return to normal position after the handle 72 has been released. A link 98 is pivoted at its upper end to the arm 96, and the lower end of the link 98 is pivoted to a lug 99 rigid with the lower end of the inlet portion 61 of the siphon. Consequently, when the handle 72 is depressed, an upward pull will be imposed upon the lower end of the siphon's inlet portion 61, and since the direction in which this pull is exerted is offset laterally from the point on the bottom 13 of the tank to which the outlet portion 31 of the siphon is connected, the effect of this upward pull is to bend the flexible portion 52 of the siphon, causing the bend 62 at the upper portion of the siphon to swing to the right and downwards from the full line position in Figure 2 to the dotted line position. In this latter position the entire siphon tube is submerged, with the result that siphonic action will start within the siphon tube as hereinabove described, thus causing water to be discharged from the tank 11 through the siphon tube and thence through the discharge pipe 12. The flow of water thus induced will continue until a sufficient quantity of water has been withdrawn from the tank 11 to permit air to enter the siphon tube and thus break the siphonic action.

In some instances it may be satisfactory to permit air to enter the opening 63 in the inlet end of the siphon tube, under which circumstances the siphon tube should be so designed that when it is in its most nearly upright position the opening 63 at the inlet end of the siphon tube is closely adjacent the desired low water level within the tank 11. However, under other circumstances it may be desirable to provide especial means for permitting air to enter the siphon tube for the purpose of breaking siphonic action. An auxiliary air inlet tube 101 may be affixed to the inlet portion 61 of the siphon tube, the open lower end 102 of the air inlet tube 101 being disposed adjacent the lower end of the siphon's inlet portion 61 and the upper end 103 of the air inlet tube 101 opening into the interior of the bend 62. As the result of this arrangement, when sufficient water has been withdrawn from the tank 11 to uncover the open lower end 102 of the air inlet tube, air will be admitted to the bend 62 of the siphon tube and thus cause discontinuance of the siphonic action.

The finger 73 has the upper end of a push rod 106 pivoted thereto, the lower end of the push rod 106 being engaged with a valve 107 reciprocal within the valve housing 86. The valve 107 is provided with two passages 108 and 109 therethrough, and the parts are so arranged that when the finger 73 is in its raised position, as illustrated in Figure 1, the valve 107 will occupy its uppermost position wherein the passage 108 interconnects the two ports 111 and 112 through which the opposed portions of the delivery tube 83 communicate with the interior of valve housing 86; and when the finger 73 is turned clockwise, as viewed in Figure 1, the valve 107 will be

lowered, bringing the alternative, obliquely extending passage 109 into position for its lower end to register with the port 111 and its upper end into registry with a port 113 which leads directly into the tank 11.

When the handle 72 is depressed, the shaft 71 is rotated counter-clockwise, carrying with it the finger 73 so that it passes from the deeper recess 74 into the shallower recess 79. This forces the arm 76 downwards, moving the float 82 substantially to the position illustrated in Figure 1 and opening the valve within the housing 77, thus causing water to be delivered through the tube 83. As hereinabove pointed out, when the finger 73 moves upward into the shallower recess 79, it raises the valve 107 so that its straight passage 108 interconnects the two opposed portions of the delivery tube 83. Consequently, all of the water delivered through the water supply valve will, so long as the finger 73 remains within the shallower recess 79, be jetted upwards into the inlet portion 61 of the siphon tube, thus causing all of the water flowing through the siphon tube to travel at greater velocity and thereby increasing the efficiency of the flushing operation. Moreover, the presence of the jet of water entering the inlet portion 61 of the siphon tube facilitates prompt initiation of siphonic action within the siphon tube, it being understood that the action of submerging the siphon tube and commencement of flow through the flexible nozzle 88 occur simultaneously.

Owing to the upward pressure exerted by the arm 76 against the finger 73 because of the tendency for the float 82 to rise to the surface of the water into which it has been submerged, the finger 73 and the valve 107 will remain in the respective positions thereof illustrated in Figure 1, for an appreciable period after the handle 72 has been actuated, the length of that period being determined by the depth to which the float 82 is submerged, the quantity of water stored within the tank 11 above that depth, and the rate at which that quantity of water is withdrawn from the tank through the siphon tube. However, when sufficient water has been withdrawn from the tank 11 for the level of the water to fall below the position at which the float 82 was submerged by depressing the handle 72, the float 82 will move to a lower position, permitting the arm 76 to move away from the finger 73, thus releasing the finger 73 from the recess 79 whereupon gravity, acting upon the weight 97, will return the finger 73, the shaft 71, and the handle 72 to their initial positions. Thus will the finger 73 move back into proper position for it to be received within the deeper recess 74 when the float 82 again rises; and this movement of the finger 73 will be accompanied by the lowering of the valve 107 with the result that thereafter the water delivered through the delivery tube 83 no longer will be jetted into the siphon tube, but will be delivered directly to the interior of the tank 11 outside the siphon tube.

Consequently, when the tank 11 has been so nearly emptied that the level of the water then remaining in the tank is below either the open lower end 102 of the auxiliary air inlet tube 101, or below the opening 63 at the lower end of the siphon tube's inlet portion, as the case might be, air will enter the siphon tube, breaking the siphonic action as hereinabove indicated. Consequently, escape of water from the tank 11 will cease and the tank again will be filled by water escaping through the port 113 of the valve hous-

ing 86 until the rising water within the tank raises the float 82 and closes the water supply valve within the housing 77.

When the siphonic action is broken, the inlet portion 61 will be full of water and it will flow backwards within the inlet portion 61 because the level of the water then remaining in the tank 11 is at or adjacent the inlet portion's lower end 63. It has been found that if this water is permitted to rush unrestrictedly into the tank 11, it is apt to be undesirably noisy, and it is for the purpose of retarding this flow back into the tank that the cup 92 is provided upon the upwardly directed portion 87 of the delivery tube 83 immediately below the inlet end 63 of the siphon tube.

Figure 5 illustrates a modification of the siphonic flushing apparatus of the present invention wherein the siphon tube 121, instead of containing a portion which is laterally flexible, is provided with a section 122 of tubing within its outlet portion 123, which section is of resiliently flexible material. The section 122 is provided with a plurality of circumferentially extending corrugations 124, thus defining a bellows capable of variation in length with the result that the bend 126 and outlet portion 127 of the siphon tube 121 can move vertically. In its upper extreme of movement, the bend 126 is above the high water level within the associated tank 128, as illustrated in full lines, with the result that siphonic action will not start until the bend 126 is lowered substantially to the position illustrated in broken lines in which position the bend 126 is completely submerged and siphonic action will start, as explained hereinabove in connection with the first described modification.

Such lowering of the siphon tube 121 is attained by means of a rod 131 extending laterally from an arm 132 pivotally mounted upon a valve housing 133 supported at the upper end of a water inlet tube 134. The rod 131 engages a bracket 136 rigid with the bend 126 of the siphon tube 121 in such a manner that when the arm 132 is rotated clockwise, as viewed in Figure 5, the bend 126 will be lowered against the inherent expansive resiliency of the material of which the bellows tube 122 is composed. A vertical guide rod 137 rigidly secured to the stationary lower end of the siphon tube's outlet portion 123 as by a bracket 138 extends past the bellows section 122 and is slidably engaged within the eye 139 at the outer end of a bracket 141 rigid with the movable portion of the siphon tube's outer portion 123 above the bellows section 122.

As in the previously described modifications, the arm 132 is provided with two recesses, 146 and 147, the former being deeper than the latter, i. e., the bottom of the recess 146 is disposed at a greater radial distance from the operating shaft 148 than is the bottom of recess 147. Consequently, when a finger 149 carried by the shaft 148 is swung counter-clockwise from the position in which it is illustrated, it will leave the deeper recess 146. This swings the arm 132 clockwise and forces a float 151, which is operably connected to the arm 132, deeper into the water within the tank 128. The finger 149 will seat within the shallower recess 147 where it will be retained by pressure of the arm 132 thereagainst because of the tendency for the float 151 to rise within the water, with the result that a valve 156 operably connected to the finger 149 by a push rod 157 will be retained in its uppermost position 75 with a horizontally extending passage 157A

therein interconnecting the opposed portions of the water delivery tube 158, as long as the finger 149 remains within the shallower recess 146.

Consequently, delivery of water directly into the siphon tube 121 from the water supply tube 134 will be maintained until a sufficient quantity of water has been withdrawn from the tank 128 to permit further lowering of the float 151 from the position to which it was forced when the finger 149 was moved into the shallower recess 146. For the purpose of prolonging this time, I prefer to provide a baffle 161 upon the upper end of the vertically extending portion 162 of the delivery tube 158 within the lower end of the siphon tube's inlet portion 127. Preferably a cylindrical housing 163 closed at its lower end 164 and having a plurality of orifices 166 in its side wall is also provided upon the vertically extending portion 162 of the delivery tube 158, the upper end of this housing being open and extending past the baffle 161. The outside diameter of this housing 163 is only slightly less than the inside diameter of the inlet portion 127 of the siphon tube, and the diameter of the baffle 161 is only slightly less than the inside diameter of the housing 163, with the result that the housing 163 of the baffle 161 cooperates in retarding the rate at which water stored within the tank 128 will be siphoned therefrom.

The retardation in the rate of discharge of water stored within the tank 128 thus attained is a feature of importance inasmuch as it makes it possible to comply with the local ordinances requiring that each flushing operation must provide not less than a specified minimum quantity of water and still use a materially smaller tank than would be necessary were reliance placed solely upon the water stored within the tank to provide the required quantity. In fact, it has been found by actual experimentation that it is entirely satisfactory to employ a tank 128, the capacity of which is in the neighborhood of only 2½ gallons, and to retard the rate at which the 2½ gallons stored within the tank is withdrawn therefrom to such an extent that 5½ or 6 gallons or even more water is delivered through the tank's discharge pipe 171 before the level of the water within the tank reaches the inlet end of the siphon tube 121 to break the siphonic action. A flush tank of such small capacity is a particularly desirable feature inasmuch as it could be shaped for reception between normally spaced studs and thereby substantially concealed within a wall construction. This not only would yield a more attractive appearance from an architectural standpoint, but also would save valuable space by avoiding the necessity of employing a flush box protruding into the room space.

Because of these details the embodiment of siphon tube 121, illustrated in Figure 5, is particularly advantageous since it requires no lateral movement and, therefore, is better adapted than the first-described laterally movable siphon tube, the lateral displacement of which requires more side clearance within the tank 128 than the vertically moving siphon 121.

In the modification of siphon tube illustrated in Figures 7 to 10 inclusive, a telescopic outlet section 176, a movable inlet portion 177, and bend 178 are provided. The telescopic section 176 comprises a stationary section 181 into the upper end of which the lower end of a movable section 182 extends. A slidable, substantially watertight seal is established between the sec-

tions 181 and 182 through the expedient of a packing ring 183 carried within an annular recess 184 and the under surface of a radial flange 186 of a collar 187. The cylindrical flange 188 of the collar 187 is interiorly threaded for its reception upon the upper end of the stationary section 181 so as to position the collar 187 rigidly but removably thereupon. Within the stationary section 181 and below the collar 187, the movable section 182 is provided with a collar 191 which is rigid but removably fastened in position upon the movable section 182, preferably through the expedient of an exteriorly tapered, downwardly extending cylindrical flange 192 which is radially slotted at spaced intervals throughout its circumference as indicated at 193. This cylindrical flange 192 has a tapered thread 194 formed on its outer surface for the reception of a complementary threaded ring 196 which, when tightened upon the threaded flange 192, causes the flange 192 to be squeezed tightly against the movable section 182 to anchor it firmly thereupon.

Extending upwardly from the collar 191 is a cylindrical flange 197 having a relatively sharp annular edge 198 and its upper end engageable with the packing 183 to provide a substantially watertight seal between the sections 181 and 182 when the movable section 182 is at its upper extreme of movement. A coil spring 201 is under compression between a spider 202 disposed within and rigidly secured to the stationary section 181, and an upper spider 203 carried by the movable section 182. The upper spider 203 is adjustable so as to make possible the variation in the force with which the spring effects seating of the sharp edge 198 against the packing 183. Such adjustment is attainable by means of an adjusting screw 204 threaded through a suitable bushing 206 rigidly seated in a wall of the movable section 182, the inner end of the screw 204 being seated within a cup 207 rigid with the spider 203 and spaced thereabove as by a plurality of rods 208.

I claim:

1. In flushing apparatus of the class indicated for discharging water from a flush tank, a discharge pipe leading from said tank, a siphon tube movably mounted within said tank and communicating with said discharge pipe, means for lowering said siphon tube within water contained within said tank, means for jetting a stream of water into the inlet of said siphon tube, means cooperatively associated with said lowering means for actuating said jetting means as said lowering means is operated, means operative upon release of said submerging means for moving said siphon tube to a position wherein its inlet is adjacent the low water level within said tank, means for maintaining said stream within said siphon tube substantially until the level of water within said tank falls to said low water level, and means operative substantially as the surface of the water within said tank reaches said low water level for directing the water of said stream into said tank outside of said siphon tube.

2. In flushing apparatus of the character described, a storage tank, a discharge pipe leading from said tank, a siphon tube movably mounted within said tank and communicating at its outlet end with said discharge pipe, means for supplying water under pressure to said tank, a supply valve associated therewith, a delivery tube leading from said valve, means associated with said delivery tube for jetting water from said tube into the inlet end of said siphon tube, a float

11

operably connected to said supply valve to open and close that supply valve by moving downwards and upwards, respectively, within said tank, a deflector valve interposed within said delivery tube for optionally directing water passing through said tube to said jetting means or to the interior of said tank outside said siphon tube, manually operable means for simultaneously lowering said float to open said supply valve and moving said deflector valve to that position thereof wherein water is delivered to said jetting means, means operable while said siphon tube is in lowered position for restricting flow of water stored within said tank into said siphon tube, 10 releasable means for retaining said siphon tube in lowered position, means operable when the water level within said tank has dropped to a predetermined lower level for releasing said siphon tube, and means for returning said siphon tube to its upper position upon release of said retaining means.

3. In flushing apparatus of the character described, a storage tank, a discharge pipe leading from said tank, a siphon tube movably mounted within said tank and communicating at its outlet end with said discharge pipe, means for supplying water under pressure to said tank, a supply valve associated therewith, a delivery tube leading from said valve, means associated with said delivery tube for jetting water from said tube into the inlet end of said siphon tube, a float operably connected to said supply valve to open and close that supply valve by moving downwards and upwards, respectively, within said tank, a deflector valve interposed within said delivery tube for optionally directing water pass-

ing through said tube to said jetting means or to the interior of said tank outside said siphon tube, manually operable means for simultaneously lowering said float to open said supply valve and moving said deflector valve to that position thereof wherein water is delivered to said jetting means, means operable while said siphon tube is in lowered position for restricting flow of water stored within said tank into said siphon tube, releasable means for retaining said siphon tube in lowered position, means operable when the water level within said tank has dropped to a predetermined lower level for releasing said siphon tube, and means for returning said siphon tube to its upper position upon release of said retaining means, said deflector-valve moving means also being retained in said jet-operating position by said retaining means until release thereby of said siphon tube.

JESSE C. OWENS.
